Abbott & Sonnenfeld Design for the complete
Cabinet January 6, 1882
Safety Cabinet and Cook's Cabinet in one.

Des. 432

James G. Abbott & Archibald Lawrence,
Of Phila. Penna.
Letters Patent No 432. Dated Jan'y 6th 1853.

The schedule referred to in these Letters Patent and making
part of the same -

To all whom it may concern:

Be it known
that We James G. Abbott & Archibald Lawrence, of the city of
Philadelphia in the County of Philadelphia, & state of Pennsylvania
have invented or produced a new & original design for the exter-
nal decoration of a Stove Called

"Abbott and Lawrence's complete Cook"
and we do hereby declare that the following is a full & exact
description of the same -

2

Des. 432

Fig 1, is a side elevation of the stove. -

Fig 2, is a front elevation.

A, B, C, D, E, F, G, H, I, J represent foliated ornaments in
bas relief cast upon the front & side plates. The panelling containing
these ornaments are cast after the pattern represented in the drawings.

Having thus described & represented our new
design of stove plates for "the Complete Cook" what we
claim as new & desire to secure by Letters Patent is the design
and configuration of ornamental stove plates substantially
as described represented at A, B, C, D, E, F, G, H, I, J, of the
accompanying drawings -

In testimony whereof, We have hereunto signed
our names before two subscribing witnesses. -
